UNITED STATES PATENT OFFICE

153,054

DESIGN FOR A FLACON FOR PERFUME

George H. Wolfe and Dorothy E. Mackenzie-
(Wolfe), Kalamazoo, Mich.

Application November 7, 1946, Serial No. 134,589

Term of patent 3½ years

(Cl. D58—8)

To all whom it may concern:

Be it known that we, George H. Wolfe and Dorothy E. Mackenzie-(Wolfe), citizens of the United States and both residents of Kalamazoo, in the county of Kalamazoo, State of Michigan, have invented a new, original, and ornamental Design for Flacon for Perfume, of which the following is a specification, reference being had to the accompanying drawing, forming part thereof.

In the drawing—

Figure 1 is a plan view of a flacon for perfume, showing our new design, and

Figure 2 is an elevation of the flacon for perfume.

We claim:

The ornamental design for flacon for perfume, as shown.

GEORGE H. WOLFE.
DOROTHY E. MACKENZIE-(WOLFE).
